T. KEEPFER.
HAT SECURING DEVICE.
APPLICATION FILED AUG 21, 1913.

Patented Nov. 10, 1914.

UNITED STATES PATENT OFFICE.

THOMAS KEEPFER, OF PHILADELPHIA, PENNSYLVANIA.

HAT-SECURING DEVICE.

1,116,896.

Specification of Letters Patent. Patented Nov. 10, 1914.

Application filed August 21, 1913. Serial No. 785,840.

To all whom it may concern:

Be it known that I, THOMAS KEEPFER, a citizen of the United States, residing in the city and county of Philadelphia, State of Pennsylvania, have invented a new and useful Hat-Securing Device, of which the following is a specification.

My invention consists of a device for securing a lady's hat in position, the same being composed of separate members fitted telescopically to each other, adapting the pin proper thereof to be adjusted in length in the retaining member thereof, the latter named member being composed of a slotted sleeve, a collar on one end thereof and a closure on the other end thereof and a handle in which said sleeve is contained and concealed, whereby said pin proper is prevented from disconnection from said retaining member in either direction of its adjustment and said sleeve does not enter the head-gear and pass through the hair, this being accomplished by the pin only, as will be hereinafter set forth, the novel features 25 being pointed out in the claims.

The invention is satisfactorily illustrated in the accompanying drawing, but the important instrumentalities thereof may be varied, and so it is to be understood that the 30 invention is not limited to the specific arrangement and organization shown and described.

Figure 1 represents a perspective view of a hat securing device embodying my invention. Fig. 2 represents a partial longitudinal section and partial side elevation of a portion thereof, on an enlarged scale. Fig. 3 represents a partial longitudinal section and a partial side elevation of another portion thereof, on an enlarged scale. Fig. 4 represents a perspective view of a portion of the pin proper of the device. Fig. 5 represents a perspective view of the retainer and a portion of the pin proper in 40 position therein. Fig. 6 represents a transverse section on line $x-x$ Fig. 5, on an enlarged scale. Fig. 7 represents a plan view of the retainer in primary condition.

Similar numerals of reference indicate 50 corresponding parts in the figures.

Referring to the drawings:—1 designates a hat pin proper, the end opposite to the point thereof being provided with a laterally extending tongue or lug 2. The head 55 portion of said pin is fitted in the sleeve 3, which is formed with a longitudinally-ex-

tending passage 4 which is adapted at certain times to be occupied by portions of the pin 1 and the tongue 2, so that in their motions in opposite directions they may play 60 thereon. In one of the walls of the passage 4 are the recesses 5 which are in communication with said passage so that by turning the pin 1, the lug 2 may enter either of said recesses relatively to the adjusted position 65 of the pin in the sleeve 3. On the head end of the sleeve is the collar 6 which is of less diameter than that of the pin 1 with its tongue 2, so that the pin cannot pass through said collar. On the opposite end 70 of the sleeve is the collar 7, which is of less diameter than that of the pin with its tongue 2, so that the pin cannot pass through said collar 7, it being evident that by these means the pin is prevented from 75 disconnection from the sleeve 3 as its retaining device. The recesses 5 extend at inclinations to the passage 4, so that when the tongue 2 occupies either of said recesses relatively to the adjustment of the pin, owing 80 to the tendency of the pin when on the head of the wearer to move into the retainer, said tongue will be prevented from slipping laterally from said recess and so will remain interlocked with the sleeve in the relative 85 recess. On the side of the pin are graduation marks 8 which are gaged or spaced-apart relatively to the distance between the recesses 5. The sleeve is cemented or otherwise secured within the head 9, and it serves 90 to provide a convenient handle for the device and conceals said sleeve and adjacent portions of the pin with their appurtenances and while thus concealing and comparatively covering said sleeve within the length 95 of said handle, prevents the passage of the sleeve through the head-gear and hair, the pin itself thus being the only portion of the device that is adapted to engage the hair and pierce the head-gear.

It will be seen that by turning the pin and manipulating the same, the tongue will leave the recess that it occupies when the pin may be moved in or out of the sleeve so as to adjust the portion of the former 100 outside of the retainer relatively to the extent that may be required of the pin for taking proper hold of the hair of the head of the wearer and the size of the crown of the hat. Then the pin is turned so that the 105 tongue 2 enters the recess in register with it, exactness of this being occasioned by noticing

ing the graduation mark on the pin at the outer end of the sleeve 7 and placing the graduation on line with said end. The pin may now be passed through the hat and hair of the wearer and worn as usual retaining the hat on the head, the adjustment of the pin being preserved.

It will be noticed, referring to Fig. 7, that in order to insert the head end of the pin in the sleeve as the tongue 2 and said end of the pin are of greater diameter than the collar 7, the latter is formed primarily of a piece 3^x of metal or other material with a lateral projection 10 on one end, said piece having also on its other end the projection 11. Then the piece is bent up into the form of the sleeve and the proper portion of the pin placed therein. The projections 10 and 11 are curled or bent over the adjacent portions of the pin so as to join the end portions of the sleeve forming the collars 6 and 7, which though closed, are split or divided in longitudinal direction, and form the stops for the tongue to control the motions of the pin in opposite directions in the sleeve, while preventing the disconnection of the pin from the retainer, as hereinbefore described.

As the collar 6 is somewhat small, its end space is filled with a material forming a plug which comprises a closure 13 and prevents any possible protrusion of the head end of the pin through the head end of the sleeve and contacting with the end of the bore of the head 9, whereby pressure of the pin upon and working against said head is prevented. The shoulder 6 is necessarily short and light, and so liable to give or yield toward the adjacent end of the bore of the handle and have the lug 2 jam in the joint of said shoulder with the wall of the adjacent recess 5, but here the plug 13 braces said shoulder from within, and forms an abutment with the end of the bore and this vastly strengthens said shoulder, a feature of importance when the device is removed from the hat and the pin is thrust forcibly into the sleeve for fully folding it therein, the lug then striking the shoulder 6 with forcible effect, which would be injurious to the latter were it not resisted by the plug as above stated. As the collars are longitu-

dinally divided, as has been stated, they may be closed to a greater or less extent so as to properly embrace the contiguous portion of the pin and conform to variations in the thickness of different pins, and close sufficiently against the pin so as to prevent lost motion, wobbling or rattling of the latter. The outer face of the lug 2 is rounded, as at 12, so as to conform to the curvature of the outer surface of the sleeve and rest in the respective recess flush with said surface, thus avoiding any engaging contact with the bore of the head 9. When the pin is inserted into the sleeve to full extent, the length of the device is accordingly shortened, so as to be convenient for packing and carrying when not in use.

Having thus described my invention what I claim as new and desire to secure by Letters Patent, is:—

1. A hat retaining device composed of a pin having a laterally extending lug on the head end thereof, a tubular sleeve adapted to receive said pin, said sleeve having in its wall a longitudinally-extending passage, and a series of recesses extending from said passage, either of which recesses is adapted to receive said lug, inturned shoulders on the opposite ends of said sleeve adapted to close the relative ends of said passage, and a handle which is adapted to receive said sleeve and cover the latter and said lug.

2. A hat retaining device composed of a pin having a laterally extending lug on the head end thereof, a tubular sleeve adapted to receive said pin, said sleeve having in its wall a longitudinally-extending passage, and a series of recesses extending from said passage, either of which recesses is adapted to receive said lug, inturned shoulders on the opposite ends of said sleeve adapted to close the relative ends of said passage, a handle which is adapted to receive said sleeve and cover the latter and said lug, and a plug which is located in the inturned shoulder at the inner end of said sleeve.

To the above I have signed my name.

THOMAS KEEPFER.
